AUTOMOBILE DISK WHEEL

Erwin B. Kolt, Birmingham, Mich., assignor to The Budd Company, Philadelphia, Pa., a corporation of Pennsylvania

Filed June 3, 1964, Ser. No. 80,262

Term of patent 14 years

(Cl. D14—30)

FIG. 1 is a perspective view of my new design for an automobile disk wheel;

FIG. 2 is an enlarged half-front elevation of the automobile disk wheel of FIG. 1;

FIG. 3 is an offset full section taken at lines 3—3 of FIG. 2;

FIG. 4 is an enlarged partial section taken at lines 4—4 of FIG. 2;

FIG. 5 is a section taken at lines 5—5 of FIG. 3.

The essential features of the design reside in the automobile disk wheel shown in full lines in the drawing.

I claim:

The ornamental design for an automobile disk wheel, substantially as shown and described.
